UNITED STATES PATENT OFFICE

GEORGE E. SLATER, OF UNIONVILLE, INDIANA.

GATE.

SPECIFICATION forming part of Letters Patent No. 731,716, dated June 23, 1903.

Application filed December 8, 1902. Serial No. 133,752. (No model.)

To all whom it may concern:

Be it known that I, GEORGE E. SLATER, a citizen of the United States, residing at Unionville, in the county of Monroe and State of Indiana, have invented a new and useful Gate, of which the following is a specification.

This invention relates to gates, more particularly to balanced sliding gates, and has for its object to produce a simply-constructed and easily-operated gate which is perfectly balanced, so that it can be operated with the minimum of power, while at the same time possessing the requisite strength to effectually withstand all strains to which it will be subjected.

The invention consists in certain novel features of construction, as hereinafter shown and described, and specified in the claim.

In the drawings illustrative of the invention, in which corresponding parts are designated by like denoting characters in all the figures, Figure 1 is a perspective view of the gate partially open. Fig. 2 represents an enlarged detail view of the combined automatic guide or gravity-catch for supporting the gate in its closed position. Fig. 3 is an enlarged cross-section on the line 3-3 of Fig. 1.

The gate is portable or mounted upon an independent and movable supporting base or frame, so that it can be readily moved from place to place, and the structure of this supporting-frame, which will be somewhat longer than the travel of the gate, is one of the novel features of the invention. This frame consists of transverse footing members 10 11, with spaced standards or posts 12 13 rising from the foot member 10, and similar-spaced standards or posts 14 15 rising from the foot member 11, as shown, the foot members 40 and their attached standards being located at and forming the end members of the frame, as shown. The foot members 10 11 are connected by a bottom rail 16, with its ends between the standards and embraced thereby, and the connection further strengthened by diagonal braces 17 18 19 20 between the standards and the bottom rail, as shown. The braces 17 18 are still further supported by reversed diagonal braces 21 22. Longitudinal 50 guide-strips 23 24 are arranged, respectively, between the braces 17 and 19 and between the braces 18 and 20 to prevent undue lateral movement to the gate, as hereinafter explained.

At their upper ends the standards 12 13 14 15 are connected by a "riding-rail" 24^a in vertical alinement with the bottom rail 16, and the upper ends of the standards will be connected, respectively, by cap-plates 25 26, as shown. The standards will be supported laterally by diagonal braces 27 28 between them and the extended portions of the foot members, as shown, the whole forming a very compact, strong, and rigid supporting-frame, which may be located at any convenient point and transported whenever required. The parts will all be united by bolts or other suitable fastening means.

The riding-rail 24^a will be provided upon its upper surface with a wear-strip 29, preferably half round or oval in cross-section, and will likewise be provided with a flat wear-plate 30 upon its lower surface, these wear-plates adapted to receive the impact of the friction-rollers upon the traveling gate, as hereinafter shown.

The gate is designed to travel between the spaced standards and is constructed of a main frame consisting of a bottom member 31, top member 32, and end members 33 34, suitably bolted or otherwise secured together, the length of the frame being considerably greater than the opening which it is designed that the gate shall fill.

Connected between the rails 31 32 is a vertical intermediate member 35, this member so located that when the gate is closed it will come just inside the standards 14 15. The gate-frame is also provided with a longitudinal intermediate rail 36, connected by its ends to the end members 33 34 and extended beyond the member 34, as shown at 37.

The panel formed by the members 31, 36, 33, and 35 is preferably filled by wire fencing material of any approved design.

The shorter panel formed between the members 35 and 34 will preferably be strengthened by reversely-disposed diagonal braces 39 40, as shown, to increase the rigidity of this part of the structure.

At its rear end the gate-frame will be provided with a bearing-roller 41, adapted to travel in engagement with the under side of the rider-rail 24^a and against the wear-plate 30, while another bearing-roller 42 will be rotatively disposed between the brackets or side supports 43 44, attached to opposite sides of

the member 35 and extending above the riding-rail 24^a, so that the roller 42 will be supported in position to travel upon the wear-strip 29, as shown.

5 The roller 42 will be formed with a peripheral groove to enable it to "grip" the wear-plate and prevent lateral displacement therefrom and to cause the gate to travel without coming in contact with the supporting-framework.

10 The brackets 43 44 serve an important purpose in supporting the roller 42 equally from each side and preventing unequal lateral movement or strains and likewise effectually preventing the displacement of the gate.

15 Rotatively disposed between the standards 14 15 is another bearing-roller 45, with which the lower edge of the longitudinal member 32 engages as the gate is operated.

20 The member 32 is preferably T-shaped in cross-section, and the roller 45 will be grooved to receive this member, and thus serve as a guide to prevent any lateral movement of the gate.

25 The portion of the gate between the members 34 and 35 will be made sufficiently heavy to perfectly balance the longer portion of the gate, so that the gate will be poised upon the roller 42 as a center. Hence when the gate

30 is operated it is not necessary to lift any portion of its weight, but merely to move it longitudinally upon its bearing-rollers. By this simple arrangement the gate may be operated with great ease and will require the expenditure of a relatively small amount of power and can be operated by small children as well as adults.

35 The framework can be constructed of comparatively light material, and by reason of the uniformly-disposed bracing and strengthening features will possess ample strength to withstand all the strains to which it will be subjected.

40 The rear member 34 may be provided with a counterweight embedded therein, as shown at 46 in Fig. 3, and entirely concealed by the material forming the end member to insure the requisite "balance" to the gate.

45 The post at the opposite side of the driveway is illustrated at 47 and will be of any suitable size and will be provided with spaced wings 48 49, adapted to engage the opposite sides of the member 33 when the gate is closed and prevent lateral movement of the free end 50 of the gate at its lower edge.

50 At a point opposite the projecting end 37 of the member 33 is located a combined stop or support consisting of a plate 50, having extended side walls 51 52, connected by a trans-

55 verse bolt 53, carrying a friction-roller 54, with which the projection 37 engages as the gate is closed to cause the gate to be slightly elevated and serving as a guiding means for conducting the projection 37 into an aperture 54 in the plate 50, as shown.

60 The entrance to the aperture 54 is inclined,

as at 55, to still further assist in guiding the part 37 "home" into the aperture. By this simple means when the gate is closed the projection 37 will be guided into the aperture 54 7c and, at the same time the gate is slightly elevated and a portion of its weight thereby transferred to the plate 50, so the gate will be supported with sufficient force by its own gravity to prevent accidental displacement, 75 while at the same time it will be sufficiently yieldable to be readily opened when the necessary force is applied.

The gate structure may be modified to any desired extent to fit any size of driveway or 80 other opening and may be readily adapted to gates of all sizes and to gates employed in all the various localities where similar structures are required.

The supporting-framework will be located 85 behind the fence or other structure adjoining the driveway or other opening, and the spaced guide-rails 23 will prevent any undue lateral movement of the gate structure.

Any suitable arrangement of the fencing 90 material may be employed, but will preferably be finer at the lower part to prevent the passage of small animals or fowls when the gate is closed.

Having thus described my invention, what 95 I claim is—

In a gate, a supporting-frame comprising spaced standards disposed in pairs and forming the opposite ends of the frame, a bottom rail and rider-rail connected by their opposite ends between the opposite ends of the standards and forming dividing means thereto, a bearing-roller rotatively mounted between one pair of said standards, foot members connected to said standards and extending laterally therefrom, diagonal braces between said standards and bottom rails, and spaced horizontal guard-rails between said diagonal braces upon opposite sides of said bottom rail and spaced therefrom, in combination 105 with a gate member movably disposed between said standards and having a longitudinally-disposed top rail in movable engagement with said bearing-roller, parallel spaced guide members intermediately disposed relative to said gate and extending vertically upward therefrom upon opposite sides of said rider-rail, a bearing-roller supported rotatively between said guide members and movably bearing upon the upper side of said 110 rider-rail, and a bearing-roller rotatively supported upon said gate in movable engagement with the under side of the said rider-rail, substantially as described.

In testimony that I claim the foregoing as 125 my own I have hereto affixed my signature in the presence of two witnesses.

GEORGE E. SLATER.
